US00D842130S

(12) **United States Design Patent** (10) **Patent No.:** **US D842,130 S**
(45) **Date of Patent:** **** Mar. 5, 2019**

(54) **CLOCK**

(71) Applicant: **Wuhan Zhenboshi Intelligent Technology Co., Ltd**, Wuhan (CN)

(72) Inventor: **Gang Xiao**, Wuhan (CN)

(73) Assignee: **WUHAN ZHENBOSHI INTELLIGENT TECHNOLOGY CO., LTD**, Wuhan (CN)

(**) Term: **15 Years**

(21) Appl. No.: **29/653,442**

(22) Filed: **Jun. 15, 2018**

(30) **Foreign Application Priority Data**

Jan. 9, 2018 (CN) 2018 3 0008277

(51) LOC (11) Cl. **10-01**

(52) U.S. Cl.

USPC **D10/26**

(58) **Field of Classification Search**

USPC D10/1-29, 40, 41, 128-130; D14/170, D14/171, 188, 194, 195, 197, 198

CPC G04B 19/00; G04B 19/04; G04B 19/34; G04B 45/0069; G04C 3/00; G04C 3/0001

See application file for complete search history.

(57) **CLAIM**

The ornamental design for a clock, as shown and described.

DESCRIPTION

FIG. 1 is a perspective view of a clock showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line disclosure is for illustrative purpose only and forms no part of the claimed design.
